UNITED STATES PATENT OFFICE.

JESSE H. SROFE, OF KOKOMO, INDIANA.

DESIGN FOR A FENCE.

SPECIFICATION forming part of Design No. 31,602, dated October 3, 1899.

Application filed August 21, 1899. Serial No. 728,012. Term of patent 7 years.

To all whom it may concern:

Be it known that I, JESSE H. SROFE, a citizen of the United States, residing at Kokomo, in the county of Howard and State of Indiana, have invented and produced a certain new Design for a Fence, of which the following is a specification.

The drawing shows an elevation of a fence-panel embodying my new design.

As shown in the drawing, the leading or material feature of my design consists of the fence having the several horizontal or cross strands A, B, C, D, and E, the pickets F, having the curved tops f, which cross each other and overlap, as shown, above the strand A, and the straight vertical pickets G. These pickets have inclined portions f', which converge toward each other between the strands A and B and meet at strand B, crossing each other between the strands A and B. Then follow the parallel vertical portions f² between the strands B and C, making an angular bend, when the direction changes from the diagonal to the vertical, and between the strands C and D are the inclined portions f³, diverging from the vertical position with an angular bend and crossing corresponding portions of adjacent pickets, and then the portions f⁴, inclined and converging in the space

between the strands D and E, the members of adjacent pickets crossing each other, as shown, and the lower end portions f⁵, which diverge below the lower strand E, such lower portions being arranged in pairs and the portions of each pair diverging, and all of the bends being angular ones, as shown. The pickets G are between the parallel portions f² and contact with same and bisect the diamond-shaped spaces formed by the crossed portions between the strands A and B, C and D, and D and E. The pickets and the cross-strands present the appearance of twisted wire, giving the panel and pickets an appearance of a fabric. The crossings of the inclined wires produce diamond-shaped patterns and half-diamonds, as clearly shown.

Having described my invention, what I claim as new, and wish to secure by Letters Patent, is—

The design for a wire fence as herein shown and described.

In witness whereof I have hereunto set my hand and seal, at Indianapolis, Indiana, this 17th day of August, A. D. 1899.

JESSE H. SROFE. [L. S.]
